UNITED STATES PATENT OFFICE.

JOHN M. TRAVIS, OF ST. LOUIS, MISSOURI.

DESIGN FOR A SYRUP-DISPENSING APPARATUS.

51,533.

Specification for Design.

Patented Nov. 27, 1917.

Application filed August 30, 1917. Serial No. 189,035. Term of patent 7 years.

To all whom it may concern:

Be it known that I, JOHN M. TRAVIS, a citizen of the United States, residing at St. Louis, State of Missouri, have invented a new, original, and ornamental Design for a Syrup-Dispensing Apparatus, of which the following is a specification, reference being had to the accompanying drawing, forming a part hereof.

The figure is a perspective view of a syrup dispensing apparatus showing my new design.

I claim:

The ornamental design for a syrup dispensing apparatus, as shown.

JOHN M. TRAVIS.

Witnesses:

EMIL STAREK,
ELSE M. SIEGEL.
